UNITED STATES PATENT OFFICE.

PAUL H. WERNER, OF NEWARK, NEW JERSEY.

NEEDLE-THREADING ATTACHMENT FOR SEWING-MACHINES.

1,246,199.

Specification of Letters Patent. Patented Nov. 13, 1917.

Application filed February 7, 1917. Serial No. 147,036.

To all whom it may concern:

Be it known that I, PAUL H. WERNER, a citizen of the United States, residing at Newark, in the county of Essex and State 5 of New Jersey, have invented certain new and useful Improvements in Needle-Thread- 60 ing Attachments for Sewing-Machines; and I do hereby declare the following to be a full, clear, and exact description of the in- 65 vention, such as will enable others skilled in the art to which it appertains to make and use the same, reference being had to the accompanying drawings, and to characters of reference marked thereon, which form 15 a part of this specification.

The present invention has reference, generally, to improvements in needle-threading attachments for sewing machines; and, the invention relates, more particularly, to a 20 novel, simple and easily manipulated attachment for connection with the needle-bar of a sewing machine, and so related thereto that a thread-guide connected therewith may be operatively associated with the eye of the 25 needle carried by said needle-bar to enable the thread to be quickly and easily passed through the needle-eye.

The invention has for its principal object to provide a needle-threading attachment, 30 as above mentioned; and a further object of the invention is to provide a novel means for attaching the needle-threading device upon the needle-bar of the machine in such a manner, that when the same is not in use, 35 it may be readily moved to an inoperative position of the sewing machine mechanism; and a still further object of the present invention is to provide said needle-threading device with means for automatically remov- 40 ing the same from operative relation to the needle, and out of the way, should the sewing-machine be inadvertently started up.

Other objects of the present invention, not at this time more particularly enumerated, 45 will be clearly understood from the following detailed description of the same.

With the various objects of my present invention in view, the same consists, primarily, in the novel needle-threading attachment for sewing machines hereinafter set forth; and the invention consists, furthermore, in the novel arrangements and combinations of the several devices and parts, 50 as well as in the details of the construction of the same, all of which will be more fully described in the following specification, and

then finally embodied in the claims appended thereto.

The invention is clearly illustrated in the accompanying drawings, in which:— 60

Figure 1 is a front elevation of a portion of a sewing machine, showing the needle-bar and needle thereof equipped with the novel needle-threading device made according to and embodying the principles of my 65 present invention; and Fig. 2 is a side elevation of the same.

Fig. 3 is a detail longitudinal vertical section taken on line 3—3 in said Fig. 2, looking in the direction of the arrow x, 70 showing the operative relation thereto of the novel thread-guiding means of said needle-threading device, said view being drawn on a much larger scale.

Fig. 4 is a horizontal section, taken on 75 line 4—4 in said Fig. 1, looking downward, said view being also drawn on an enlarged scale.

Fig. 5 is a horizontal section taken on line 5—5 in said Fig. 3, looking downward; and 80 Fig. 6 is another horizontal section taken on line 6—6 in said Fig. 3, also looking downward.

Similar characters of reference are employed in all of the above described views, 85 to indicate corresponding parts.

Referring now to the said drawings, the reference-character 1 indicates the guide-housing of the sewing-machine in which the vertically reciprocating needle-bar 2 is 90 mounted. Connected with the lower end of said needle-bar 2, by means of the winged nut 3, or in any other suitable manner, is the downwardly projecting sewing machine needle 4, provided with the sharp pointed 95 lower end 5, adjacent to which is the usual thread-receiving eye 6.

The reference-character 7 indicates the usual vertically reciprocating foot-bar, to the lower end of which is secured the usual 100 presser-foot 8, having the bifurcated end 9, through which the needle passes during the sewing operation.

The reference-character 10 indicates the usual bed or cloth-plate, upon which the material to be sewn is supported beneath the needle 4 and presser-foot 8.

Connected with said needle-bar 2 is yoke-member 11 which embraces the same, and which is secured in a fixed position thereon 110 by means of a set-screw 12, or any other desirable form of fastening means. This

yoke-member 11 is provided with outwardly projecting perforated ears or lugs 13 adapted to support a journal or hinge-pin 14 passed therethrough. Said journal or hinge-pin 14 serves as the fulcrum of a swinging arm 15, the upper end of which is journaled or pivoted thereon.

Said journal or hinge-pin 14 may be provided at one end with a head 16, and at its opposite end with a threaded shank-piece 17, upon which is arranged a tightening nut 18, which serves to draw together said ears or lugs 13 into the desired frictional relation to said arm 15, so that the friction established offers resistance to the too free swinging movement of said arm, and tends to retain said arm in any position to which it may be moved.

Said arm 15 swings from the pivotal connection with the needle-bar in a plane at right angles to the plane of the eye 6 of the needle 4. Connected with the lower free end of said arm 15 is a thread-guiding device, comprising a shell-like member 19 open at its outer end, and tapering toward its inner end, to provide an inwardly tapering thread-guiding passage 20 terminating in a small opening 21 at said inner end adapted to be registered with the eye 6 of the needle 4, when said arm 15 is swung downwardly to register or position said thread-guiding device in operative relation to said needle 4. The said wall of said shell-like member 19 is provided with a longitudinally extending narrow slot or opening 22 communicating with said small opening 21, the same serving as an exit-opening through which the body of the thread may be withdrawn from said thread-guiding passage 20 after the end of 40 the thread has passed therethrough and through the eye 6 of the needle 4.

Secured to said arm 15, preferably above said thread-guiding device, is a stop-lug 23, which projects rearwardly toward the 45 needle 4, the same being provided at its outer end with a V-shaped notch 24, adapted to be moved against the needle 4, and to straddle the same, so as to hold the thread-guiding device against lateral movement, 50 and stopped in such a position that the small opening 21 thereof is properly registered or aligned with the eye 6 of the needle 4.

Secured in fixed or rigid relation to said arm 15, so as to swing with the latter, is a 55 downwardly and forwardly curved cam-arm 25, the same having an offset-portion or bend 26 adapted to laterally offset said cam-arm from the needle 4, so that it may readily pass the same. The lower end of said cam-arm terminates in a forwardly and downwardly inclined throw-up cam 27, the free end 28 of which is slightly extended beyond a vertical line extending through the pivotal point of said arm 15.

65 When the novel needle-threading attach-

ment is not in use, the same is swung upwardly on its pivotal connection with said needle-bar 2, and out of the way of the needle 4, the same occupying the position indicated by the dotted representation 70 thereof shown in Fig. 1 of the accompanying drawings.

When it is desired to thread the needle 4, the needle-bar 2 is raised to its upper limit of movement to lift the needle above the 75 presser-foot 8, and thus properly position the same so that ready access to its eye 6 may be had. The arm 15 is now swung downwardly, this movement thereof carrying the same toward the needle. The length 80 of said arm 15 being properly determined, the downward swinging thereof carries said thread-guiding device toward the eye 6 of the needle, and when the arm 15 is stopped by the engagement of said stop-lug 23 with the needle 4, the small opening 21 at the 85 inner end of said thread-guiding device is stopped in registration or alignment with the eye 6 of the needle, and practically in communication therewith. When the parts 90 of the device are thus operatively positioned relative to the needle 4 and its eye 6, the end of the thread, which it is desired to pass through the eye of the needle, is introduced into the tapering passage 20, the converging 95 walls of which guide the end of the thread to and through said small opening 21, and thence through the eye 6 of the needle which is aligned in communication therewith. Consequently the thread is quickly and easily 100 introduced through the eye of the needle, without necessity for straining the sight, or without necessity for any particular steadiness of hand. After the thread is thus passed through the needle-eye, the body of 105 the thread may be quickly liberated from the thread-guiding device by passing the same laterally to and through the longitudinal slot or opening 22 in the wall of said thread-guiding device, whereupon the arm 15 may 110 be swung up and back to normal initial or inoperative position, and out of the way.

If by any chance, the operator after using the thread-guiding device forgets to turn up and out of the way said arm 15, to remove 115 the thread-guiding device from operative relation to the needle, and inadvertently starts up the sewing machine, the downward movement of the needle-bar 2 carries into contact with the cloth-plate or bed 10, the free end 28 of said throw-up arms 27, such contact causing the cam to slide outwardly, thus swinging away from the needle 4 the arm 15 and the thread-guiding device connected therewith, so as to leave the needle 120 unobstructed, and free to pass through the goods to be sewn. It will thus be understood that not only is the needle freed from the obstruction of the associated thread-guiding device, but the thread-guiding de- 125 130

vice is itself thus guarded against injury or breakage through violent contact with the cloth-plate or bed 10 if the arm 15 is moved end-down toward the latter.

5 It will thus be apparent that my present invention provides a very simple yet efficient needle-threading device, which can be permanently connected with the needle-bar 2, but which is so associated therewith as to 10 be easily moved to and maintained in either operative or inoperative relation to the needle 4.

I am aware that some changes may be made in the several arrangements and combinations of the various devices and parts of 15 my present invention, as well as in the details of the construction of the same without departing from the scope of said invention as defined in the claims appended here- 20 to. Hence, I do not limit my invention to the exact arrangements and combinations of the various devices and parts as described in the foregoing specification, nor do I confine myself to the exact details of the con- 25 struction of the said parts as illustrated in the accompanying drawings.

I claim:—

1. In a device of the kind described, the combination with the needle-bar of a sewing 30 machine, of an arm pivoted thereto, a thread-guiding device secured to the lower end of said arm and adapted to be alined with the eye of the sewing machine needle when said arm is swung downward, and a 35 cam-means connected with the lower end of said arm adapted upon contact with the cloth-plate or bed of said sewing machine to swing said arm and its thread-guiding device away from the needle.

40 2. In a device of the kind described, the combination with the needle-bar of a sewing machine, of an arm pivoted thereto, a thread-guiding device secured to the lower end of said arm, a stop-means having a needle-em-

bracing device adapted to engage the sew- 45 ing machine needle connected with said needle-bar when said arm is swung downward to aline said thread-guiding device with the eye of said needle, and a cam-means connect- 50 ed with the lower end of said arm adapted upon contact with the cloth-plate or bed of said sewing machine to swing said arm and its thread-guiding device away from the needle.

3. A needle-threading attachment for sew- 55 ing machines, comprising an arm, means for pivotally connecting said arm with the needle-bar of the machine, a thread-guiding device connected with the lower end of said arm, comprising a shell-like member provid- 60 ing an inwardly converging thread-guiding passage terminating at its inner end in a small exit-opening adapted to be alined with the eye of the needle connected with said needle-bar, the wall of said shell-like mem- 65 ber having a longitudinally extending slot throughout its length communicating laterally with said thread-guiding passage and said exit-opening, a stop-lug connected with said arm having a V-shaped end adapted to 70 embrace the needle-shank when said arm is swung downward to stop said arm and to aline said exit-opening of said thread-guid- 75 ing device with the eye of said needle, a throw-up cam connected with the lower end of said arm, the free end of which extends downwardly and forwardly beneath and beyond the lower end of said arm, and means for laterally off-setting said throw-up cam from said arm.

In testimony that I claim the invention set forth above I have hereunto set my hand this 5th day of February, 1917.

PAUL H. WERNER.
